UNITED STATES PATENT OFFICE.

WILLIAM PATTERSON, OF PHILADELPHIA, PENNSYLVANIA.

AUTOMATIC FOLDING GARMENT HANGER.

Application filed September 10, 1924. Serial No. 736,930.

This invention relates to garment-hangers and provides an automatic folding garment-hanger which can be screwed or otherwise attached to a door or other support.

5 An object of the present invention is to provide a hanger which folds up and back into a case so that when the device is closed, the hanger-arms are concealed from view; the construction and arrangement being 10 such as to provide a neat, pleasing, and ornamental attachment for any door or other support.

A further object of the invention is to provide a garment-hanger in which the support-bar to which the hanger-arms are attached may be carried by a case mounted on the surface of the door or set in a recess in the door so as to be flush with the surface; means being provided for causing the 20 hanger-arms to automatically swing into and out of operative position as the support-bar is alternately raised and lowered.

Other objects and advantages of the invention may be apparent from the following 25 detailed description thereof, reference being had, also, to the accompanying drawings, wherein:—

Figure 1 is a front elevation of a section of a door or other support to the surface of 30 which the invention is shown applied and in closed position.

Figure 2 is a sectional view, on an enlarged scale, taken on line 2—2 of Figure 1.

Figure 3 is a sectional view of the garment-hanger taken on line 3—3 of Figure 2.

Figure 4 is an enlarged detail view of the hinge connection between the case and the support-bar assembly.

Figure 5 is a detail view showing a different, or inset, type of case with which the invention may be used.

Figure 6 is a front elevation of a section of a wardrobe having a modified form of the invention applied thereto.

45 Figure 7 is a longitudinal section taken on line 7—7 of Fig. 6, the hanger arm being shown within the case.

Figure 8 is a cross section of the case taken on line 8—8 of Figure 7.

50 Figure 9 is a longitudinal section showing the hanger-arms in open position beyond the case.

Figure 10 is a detail view, in perspective, of one of the hanger-arms.

Describing the invention in detail, and referring more particularly to the construction shown in Figures 1 to 5, inclusive, 10 designates the casing of the device which is long and rectangular and which is secured to the door or other support 11 in a vertical position. When the case is mounted on the surface of the door, as in Figure 2, the sides and ends of the case are tapered, or rounded, as shown at 12, and securing means 13 are passed through the tapered portions to hold 15 it in position. When the case is to be set in the door, however, the latter is provided with a recess 14 to receive the case, as shown in Figure 5, and the case is provided with an attaching flange 15 by means of which the 20 device is secured in place, the flange being countersunk so as to be flush with the surface of the door.

Within the case, and pivoted or hinged thereto, as at 16, for movement outwardly 75 thereof, is a hollow support-bar 17 having its opposite sides provided with a series of grooves 18 in each of which is accommodated a hanger-arm 19. At its outer end, the hanger-arm is provided with a knob 20 to 80 prevent the garment from slipping off the arm and at its inner end it has a hub 21. Hub 21 fits in an opening 22 at one end of the groove and is held in place by a pin 23 on which it turns when the arm moves into 85 and out of the groove. The hanger arms are operated by a straight rack-bar 24 having a curved end 25 which is anchored to the inside of the case by a fixed pin 26 operating loosely in an arcuate slot 27 in the curved 90 end. This rack-bar extends inside of the pivoted support bar 17 and is provided with a series of rack-teeth 28 which are engaged by teeth 29 on the hubs of the hanger-arms.

When the support bar 17 is lowered and raised, it carries the rack-bar with it, but the length of the slot 27 and the position of the pin 26 is such that the latter is engaged by a terminal of the slot before the support bar is fully lowered or raised. Consequently, the rack-bar is held stationary with respect to the support-bar, although free to pivot on the pin 26, with the result that further movement of the support-bar causes it to slide along the rack-bar so that 100 the stationary rack-teeth of the latter rotate the toothed-hubs of the hanger-arms, 105 causing them to swing into open or closed position,

as the case may be. The arrangement is such that the hanger-arms close against the sides of the support-bar as the latter is swung upwardly into the case and they open as the support-bar is swung downwardly from the case, the operation being automatic as the bar is raised and lowered.

In the modification shown in Figures 6 to 9, inclusive, the case 30 is passed through a suitable opening formed preferably in a top panel 31 of a wardrobe so that the case will extend inside the wardrobe. It is secured in place by any suitable means, such as by a flange 32 on the outside edge of the case and a washer 33 on the inside of the panel, bolts 34 being passed therethrough and secured by nuts 35. A stop 36 is provided at the forward end of the case to engage projections 37 at the rear end of the support bar 38, and thus prevents the bar from being entirely withdrawn from the case. A series of hanger-arms 39, similar in construction to the hanger-arms of the previously described device, are carried by the bar 38 and swung on pivot-pins 40 so as to move into and out of the longitudinal openings 41 in the sides of the bar, the shoulder 42 at the rear terminal of each opening providing an abutment against which the hanger-arm strikes when in its outermost or operative position. As in the previously described device, the hanger-arms are operated by a rack-bar, indicated at 43, which slides back and forth within the support-bar and which is geared, as shown at 44, with the hubs of the hanger-arms. In the modified form of the invention, however, the rack-bar extends outwardly beyond the front, rather than the rear, end of the support-bar and is provided at its exposed end with an operating handle or grip 45. Suitable stops 46 are also carried by the rack-bar for engaging the forward end of the support-bar to limit the forward movement of the bar. When the support-bar is within the case, as in Fig. 7, the hanger-arms lie within the openings 41 and the handle 45 of the rack-bar is close against the face of the support-bar. To open the hanger, the handle 45 is grasped and pulled outwardly but is prevented from shifting within the support-bar by reason of the abutment of the hanger-arms with the enclosing walls of the case. However, the pull is communicated to the support-bar so that the latter is thereby withdrawn from the case and as soon as the last set of hanger-arms is free of the case, the rack-bar slides forward within the support-bar, swinging the hanger-arms outwardly to the position shown in Fig. 9. The device is then ready for use.

From the foregoing it will be apparent that the invention may be embodied in several different forms and modifications and it is to be understood that further changes

in the construction, arrangement and design of the parts may be made within the scope of the appended claims.

Having thus described the invention, what I claim is:—

1. A garment-hanger including a case, a support-bar pivoted to the case for swinging movement into and out of the same, a slide member carried by the said support-bar, hanger-arms also carried by the support-bar, an operating connection between the said slide member and the said hanger-arms operating to cause the latter to be moved into and out of operative position upon the relative sliding movement of the support-bar and the said slide member, and means for causing such relative sliding movement at a predetermined time during the swinging movement of the said support-bar.

2. A garment-hanger comprising a support, a member pivoted to the support for movement outwardly thereof, a plurality of pivoted hanger-arms carried by said pivoted member, a slide member carried by the said pivoted member and operatively connected to the said pivoted hanger-arms for swinging the latter upon their respective pivots when the said members are moved relative to one another, and a connection between the said slide member and the said support operating to cause such relative movement of the members at a predetermined time during the pivotal movement of the said pivoted member.

3. A garment-hanger comprising a support, a support-bar pivoted to the support, a plurality of hanger-arms pivoted to the support-bar, a slide carried by the said support-bar and operating the said hanger-arms, and a loose pivot connection between the said support and one end of the said slide, said connection including means for causing the slide to move automatically relative to the support-bar and at a predetermined time during the pivotal movement of the said support-bar.

4. A garment-hanger comprising a case, a support-bar fitting within the case and pivoted thereto for movement outwardly thereof, a plurality of pivotally mounted hanger-arms supported on opposite sides of the said support-bar, an operating slide on the inside of the said support-bar with one end exposed therefrom and penetrating the said case, an operating connection between the said slide and the said hanger-arms, and means for causing a relatively sliding movement between the said slide and the said support-bar, said means including a fixed pin on the inside of the said case and operating in an arcuate slot in the said exposed end of the said slide.

5. A garment-hanger comprising a support-bar having a central bore and having

opposite sides provided with a series of external grooves respectively terminating at one end in an opening communicating with the said bore, a plurality of hanger-arms on the said opposite sides of the support-bar, each of said hanger-arms being shaped to fit into a groove and having a toothed hub-portion pivotally mounted in the said open-

ing at the end of the groove, and a rack-bar slidable within the said bore of the support-bar and presenting on opposite sides a series of rack-teeth in operative engagement with the said toothed hub-portions of the said hanger-arms. ¹⁰

In testimony whereof I affix my signature.

WILLIAM PATTERSON.
